DOUBLE SHEET EJECTOR

James H. O'Neill, Syracuse, N. Y., assignor to
 Continental Can Company, Inc., New York,
 N. Y., a corporation of New York

Application October 2, 1936, Serial No. 103,796

3 Claims. (CL 209—88)

The invention relates to new and useful improvements in a double sheet ejector primarily adapted for use in connection with automatic sheet feeding mechanism, as for example, in the feeding of sheet metal to a slitter. The sheets are usually stacked in a pile and the topmost sheet is lifted from the pile by suction cups and then fed to the operating mechanism. Sometimes two sheets adhere and will be lifted as one sheet and fed into the machine. The two adhering sheets are referred to as a double sheet or an abnormal sheet.

An object of the present invention is to provide a simple ejecting mechanism of few parts which is rendered operative by an abnormal sheet only for diverting the same from the feeding mechanism.

A further object of the invention is to provide a detector which will cause the ejector mechanism to be set in operation by a double sheet passing between the feed rolls, but not by a single sheet with a small irregularity or bump in its surface, or one with a bent edge.

A still further object of the invention is to provide means for releasing the whole detector unit, in case a sheet is so irregular that it becomes jammed.

The invention, in its present form, involves a mercury switch attached to a detector disk which is close enough to the feed table to be engaged and rotated by a double sheet. The mercury switch is normally open but is adapted to be closed by the turning of the disk through a predetermined angle. The width of the angle, however, is such that a minor irregularity will not rotate the detector disk far enough to close the switch.

The construction of the invention and the advantages thereof will be more particularly explained in connection with the accompanying drawings, in which—

Figure 1 is a side elevation of the detector unit, also showing diagrammatically parts of the machine with which it may be used;

Fig. 2 is an isometric sectional view, enlarged, taken along the axis of the detector unit, with the switch omitted in order to show other details;

Fig. 3 is an enlarged end view of the disk carrying the mercury switch, when in normal position;

Fig. 4 is a detail view of the disk and spring viewed from the opposite side;

Fig. 5 illustrates the position of the disk and switch as actuated by a double sheet;

Figures 6 and 7 illustrate the behavior of the switch under the influence of a buckled or irregular sheet, and

Fig. 8 is a side elevation of the sheet ejector which is set in operation by the closing of the switch.

For the purpose of illustration, the double sheet detector and ejector are shown in connection with a machine for cutting the sheet into strips. This machine comprises a table 10, over which the sheets 11 are automatically fed one by one to the feed rolls 12. This machine does not per se constitute a part of the present invention and need not be described in detail.

Whatever mechanism is used for feeding the sheets, it sometimes happens that two sheets will adhere together and thus be fed between the rolls 12. When this occurs, it is quite important that they be ejected before they reach the cutting rolls 13. For this purpose, therefore, the detector 14 is supported above the table 10 just ahead of the feed rolls 12, as shown in Fig. 1.

The detector 14 comprises a disk 15, which may be rubber, metal, wood or other suitable material. This disk is mounted to rotate on ball bearings 15a about a stud 16, which is secured by nuts 16a to a suitable supporting panel 17, with the shoulder 16b engaging the front face of the panel. The panel and stud are so supported that the disk 15 is disposed at one side of the path of travel of a normal sheet and out of contact therewith, but sufficiently close to the path so that an abnormal sheet, that is, two sheets adhering together and constituting a double sheet, will frictionally contact with and rotate the disk.

A mercury switch 18 is supported in a clip 19 carried by the disk 15. The clip is provided with slots 20 for receiving screws 21, whereby the switch is adjustably secured to the disk 15. The switch is protected by a housing 22, of which the panel 17 constitutes a part and which is provided with a hole 23 for receiving the wiring. The housing is open on its under side and is placed high enough to permit the sheets to pass therebeneath.

It will be seen from Fig. 3 that when a single sheet is fed beneath the detector, the switch will not be disturbed, but when two sheets are fed together, the disk will be engaged and rotated, as indicated in Fig. 5, and the switch will be closed. A pin 24 anchored in the disk 15 projects into the arcuate slot 25 in the panel 17. The ends of the slot 25 serve as stops for limiting the rotation of the disk in both directions. When a double sheet passes beyond the detector disk, the latter is returned to its initial position, as shown in Fig. 3, by a coiled spring 26, shown in detail in Fig. 4, one end of this spring being anchored in the disk 15 and the other end anchored in the panel 17.

The panel 17 is yieldably supported by a rigid arm 27. For this purpose, the arm is provided at its end with a hub 28, which receives a shouldered stud 29. The small end 30 of this stud is threaded into the panel 17. A torsion spring 31 is wound

- about the stud between the panel and the hub 28. A tongue 32 at one end of the spring engages a slot 33 in the panel, while a tongue 34 at the other end of the spring engages a selected one of 5 the slots 35 in the end of the hub. When a sheet fed beneath the detector is so badly crumpled that it jams against the detector housing, the latter will be rotated about the hub 28 as a center, so that the whole unit will clear.
- 10 The ejector, as shown in Figures 1 and 8, is supported on a framework 36 above the table 10 and behind the detector 14. It comprises rolls 37 driven by suitable mechanism 38 operatively connected with the machine. A feed chute 39 leading to the rolls 37 has an apron 40 carried by a rock shaft 41 which is mounted on the framework and normally held above the path of the sheets, as shown in full lines in Fig. 8. An arm 42 is secured to the rock shaft 41 and is 15 connected by a link 43 to the core 44 of a solenoid 45, which is connected by wires 46 to the switch 19 and to a suitable source of electric current.

When the switch 19 is closed, the solenoid is 20 energized, rocking the shaft 41 and moving the apron 40 to the dotted line position shown in Fig. 8, with its lower edge extending into a slot 47 in the table 10, so that the double sheet, which causes the switch to close, is ejected and passes 25 through the chute 39, between the rolls 37 and onto a raised table 48 behind the same.

It will be understood that, in the normal operation of the machine, the sheets are automatically fed one by one between the rolls 12 and to 30 the cutter, the detector and ejector remaining idle. When two sheets stick together and are thus fed between the rolls 12, the upper sheet engages the rubber disk 15 and rotates it until the pin 24 engages the upper end of the slot 25. 35 In this position, the switch 18 is closed, the solenoid 45 is energized, the apron 40 is lowered until its lower edge extends into the slot 47 in the table 10, and the double sheet is carried through the rolls 37 to the table 48, so that it is 40 not fed to the slitter or other machine which 45 the detector is designed to protect.

If a sheet is slightly buckled, as shown at 49 in Fig. 6, or if it has a heavy burr on the leading edge, high enough to engage the disk 15 as shown 50 in Fig. 7 at 50, the disk will be rotated to some extent, but not far enough to close the switch, since these slight imperfections will not seriously interfere with the normal operation of the machine.

55 If a sheet is so badly crumpled that it jams against the housing 22, the entire detector unit will be rotated about the axis of the hub 28 until the sheet clears the housing. This also will close the switch and the sheet will be ejected.

60 Whenever the disk 15 is displaced from its normal position by a double sheet or by an imperfect sheet, it is immediately returned by the spring 26, as soon as the sheet which caused the displacement has passed beyond the detector. 65 Likewise, whenever the whole unit is displaced with respect to the hub 28, it is returned by the spring 31.

70 From the foregoing description, it will be seen that the invention permits the use of automatic sheet feeding mechanism and protects the machine completely against possible injury or interference with its operation by imperfections in the sheets or in the feeding thereof. It may, of course, be used in connection with any type

of machine to which sheets may be fed, regardless of the operation to be performed on the sheets.

It is also to be understood that the construction of the invention, as herein shown and described, is merely illustrative, and that the invention also includes all such modifications as may be made within the scope of the claims hereunto appended.

Having thus described the invention, what I 10 claim as new and desire to secure by Letters Patent, is—

1. The combination with sheet feeding mechanism, of a rigid support provided with a hub above the path of the sheets, a stud rotatably 15 mounted in said hub, a housing secured to said stud, a torsion spring connecting the hub to the stud and normally holding the housing in a pre-determined position, a disk rotatably supported within the housing with a segment thereof projecting from the housing toward the path of the sheets and spaced therefrom so as to contact only with abnormally thick or double sheets, a normally open switch carried by said disk and adapted to be closed by a predetermined rotation 25 thereof, and means actuated upon the closing of said switch to eject the abnormal sheet from its normal course of travel, said housing being rotatable in opposition to said spring to allow an excessively abnormal sheet to clear. 30

2. The combination with sheet feeding mechanism, of a rigid support provided with a hub above the path of the sheets, a stud rotatably 35 mounted in said hub, a housing secured to said stud, a torsion spring connecting the hub to the stud and normally holding the housing in a pre-determined position, a disk rotatably supported within the housing with a segment thereof projecting from the housing toward the path of the sheets and spaced therefrom so as to contact 40 only with abnormally thick or double sheets, stops limiting the rotation of the disk in either direction, a spring normally holding the disk in one extreme position and returning it to such position when it is released by the sheet, a normally 45 open switch carried by said disk and adapted to be closed by a predetermined rotation thereof, and means actuated upon the closing of said switch to eject the abnormal sheet from its normal course of travel, said housing being rotatable in opposition to its spring to allow an excessively abnormal sheet to clear. 50

3. The combination with sheet feeding mechanism, of a rigid support provided with a supporting member disposed above the path of travel of the sheets, a housing pivotally mounted on said support, a spring for normally holding said housing in a predetermined position relative to the support, a disk rotatably supported within the housing with a segment thereof projecting from the housing toward the path of the sheets and spaced therefrom so as to contact only with abnormally thick or double sheets, the axis of said disk being disposed beneath the pivotal support for the housing, stops for limiting the rotation of the disk in either direction, a spring normally holding the disk in one extreme position and returning the same thereto when released by the sheet, a normally open switch carried by said disk and adapted to be closed by a predetermined rotation of the disk, and means actuated upon the closing of said switch to eject the abnormal shape from its normal course of travel. 60 65 70 75
